ENGRAVING TOOLS

Ross F. Churchill, Burlington, N.C., assignor to Western Electric Company, Incorporated, New York, N.Y., a corporation of New York

Filed Oct. 7, 1958, Ser. No. 765,904

8 Claims. (Cl. 90—24)

This invention relates to engraving tools and more particularly to an engraving tool with a nibbling head having cam-operated cutters.

The problem of stamping printed circuits composed of relatively thin sheets, such as copper, which may be mounted on insulation material, has necessitated the use of dies commonly known as "dinking" dies. These dies must have knife-edged cutting surfaces which in most instances are in the configuration of an inverted V. Attempts to etch chemically these cutting surfaces on dies have not proven satisfactory; therefore, efforts to machine such dies have been made. The instant invention is concerned with an engraving tool which has been found successful in the formation of dies such as those presently discussed.

An object of the present invention is to provide new and improved engraving tools.

Another object of the present invention is to provide a new and improved engraving tool with a nibbling head having a cam-operated cutter.

A further object of the invention is to provide a new and improved engraving tool capable of cutting in a single pass an inverted V-shaped land in a die or work-piece.

Apparatus illustrating certain features of the invention may include a housing, cam means supported within the housing, a head fixed to the housing, and cutter means supported pivotally by the head and cooperatively engaged with the cam means for oscillatory cutting action.

A complete understanding of the invention may be had from the following detailed description of a specific embodiment thereof when read in conjunction with the appended drawing, wherein:

Fig. 1 illustrates a sectional side view of a preferred embodiment of the invention;

Fig. 2 is a section of the device taken on the line 2—2 of Fig. 1 looking in the direction of the arrows;

Fig. 3 shows a section of the device taken on the line 3—3 of Fig. 1 looking in the direction of the arrows; and

Fig. 4 is a perspective view of the apparatus shown in Fig. 1 in assembly for operation with a pantograph and a machine.

Referring now to the drawing wherein like reference characters designate like or corresponding parts throughout the several views, there is shown in Fig. 1 an engraving tool 9 having a hollow housing 11, T-shaped in cross section, which may be composed of metal, such as cold rolled steel. A head 12 is slotted so as to form a rectangular cutout or passage 13 which extends from the bottom and side of the head 12 to the top and the middle thereof. In this fashion the passage 13 communicates the bottom exterior of the head 12 with hollow housing 11.

Suitable fasteners such as hexagonal head bolts 14—14 attach the head 12 rigidly to the housing 11 to close the bottom of the housing 11 thereby creating a cavity 15.

Into the cavity 15 are received stacked cams 16—16 which are aligned axially on a stepped cam shaft 17 supported vertically for rotation within bearings 18—18 held within the housing 11.

5 Cams 16—16 are shown, particularly in Fig. 3, with cam surfaces 19—19 projecting outwardly from a common vertical axis. The surfaces 19—19 on one cam 16 are spaced horizontally from the surfaces 19—19 on the adjacent cam 16 to provide equal spacing of the surfaces 10 19—19 about a vertical axis. Of course cam surfaces 19—19 may be designed in size and configuration other than that depicted in Fig. 3, which is merely illustrative of a preferred cam design.

The cutters 21—21, Fig. 1, have similarly shaped tips 15 22—22, but the blade portions 23—23 vary in height to accommodate the engagement of their cam follower portions 24—24 with their respective cams 16—16. The tips 22—22 of the blade portions 23—23 pivot in parallel planes by means of the pinned pivotal connection of the 20 cutters 21—21 within the passage 13 of head 12. The pin 25 passes through aligned apertures 26—26 provided through each of the cutters 21—21, and it is threaded at both ends, for example, to engage the threaded bore 27 (Fig. 2) formed in the head 12 for reception of the 25 pin 25.

To bear pressure constantly against cam surfaces 19—19, the cutters 21—21 are each provided with a resilient member such as springs 28—28 with their tang portions 29—29 at one end of the springs attached to a 30 rod 31 seated in apertures 32—32 (Fig. 2) of the housing 11. The tang portions 29—29 are attached at the other end of the springs 28—28 to headed retaining studs 33—33 projecting laterally from each cutting blade portion 23 intermediate the cam follower portion 24 and 35 the aperture 26. The cutters 21—21 are assembled therefor to rock back and forth about the horizontal axis defined by the pin 25.

The housing 11 and head 12 fixed thereto support 40 guidingly the cutters 21—21 for rotation axially about the cam shaft 17, but independently with respect to the rotation of the cam shaft 17. This function is achieved by the provision of a pulley 34 firmly engaged to the housing 11, while the cam shaft 17 is rotated by means of a pulley 35 fixed to the shaft 17 vertically spaced 45 apart from pulley 34 by a spacer 36 which may be composed of metal such as brass or bronze.

Referring now to Fig. 4, the setup of the instant apparatus with a pantograph may be understood. The engraving tool 9 is disposed vertically by a jig 37 above 50 a machine bed 38 onto which a workpiece or die, not shown, may be supported. A pantograph 39, which may be of conventional design, includes arms 41—41 coupled together by a vertical rod 42. The rod 42 forms also an axle on which is supported a double-grooved pulley 55 43, of which one groove in turn is coupled cooperatively by a belt 44 to the pulley 34, which, as explained hereinabove, is connected to the housing 11 of the tool 9. The other groove of pulley 43 is coupled also by a belt 45 to a pulley 46 supported for rotation with a pin 47 of the 60 pantograph 39. The pin 47 is supported for rotation about a vertical axis at the extremity of the arm 41 opposite the attachment of the block 48 with the arm 41 and with the jig 37.

In operation, the pantograph 39 utilizes a double stylus, 65 not shown, fixed to the lower end of the pin 47 which follows a master template having parallel grooves, for example, formed in the surface thereof. By the use of the pulleys 43 and 46, linked for simultaneous rotation by the belt 45, and this rotation being imparted to the 70 housing 11 via the pulley 34, any turning of the double stylus rotates the cutters 21—21 carried by the head 12. By following the radii of grooves in the master template

the cutters 21-21 will make lands which follow the radii on any pattern designed on the template.

The pulley 35, fixed to the cam shaft 17, is coupled by suitable means to a source of power, not shown, to rotate the cams 16-16 and thereby rock the cutters 21-21 in cutting action.

It is manifest that the above-described embodiment of the invention is merely illustrative and that numerous modifications may be made within the spirit and scope of the invention.

What is claimed is:

1. An engraving tool which comprises a rotary housing, independently rotary cam means supported within the housing, a head fastened rigidly to the housing for rotation therewith, about a vertical axis and cutter means engaged with the cam means and supported by the head for rotary oscillation about a horizontal axis and for rotation about a vertical axis with the head.

2. An engraving tool which comprises a rotary housing, rotary cam means supported within the housing, a head having a passage formed therethrough fixed to the housing for rotation therewith, a pair of adjacently disposed cutters having cutting edges positioned to form an inverted V-shaped configuration in cross section, the cutters supported guidingly within the passage formed in the head and pivotally about a horizontal axis, the cutters each being in operative contact with the cam means for rotary oscillatory cutting movement of the opposite half of an inverted V-shaped land in a workpiece.

3. An engraving tool which comprises a rotary housing, cam means supported for rotation within the housing, a head having a passage formed therethrough fixed to the housing for rotation therewith, and a pair of adjacently disposed cutters having cam follower portions and cutting tip portions positioned to form a V-shaped cutting surface, the cutters being supported guidingly and pivotally within the passage in the head such that the cam follower portions engage operatively the cams and the cutting tip portions depend beyond the head to cooperate to form an inverted V-shaped land in a workpiece.

4. An engraving tool which comprises a rotary housing having an inverted T-shaped cross section, a pulley attached to the exterior wall of the housing at the uppermost stem section of the inverted T-shaped cross section, a cam shaft disposed coaxially for rotation within the stem section of the inverted T-shaped cross section of the housing, a cam attached rigidly to one end of the cam shaft and positioned within the crossbar section of the inverted T-shaped cross section, a pulley located exteriorly of the housing and coupled to the other end of the cam shaft spaced coaxially with respect to the pulley attached to the housing, a head connected rigidly to the crossbar section of the inverted T-shaped cross section of the housing so as to form a cavity defined by the interior of the housing and the surface of the head, the head having formed therethrough a passage, a pair of adjacently disposed cutters each having a cam follower portion and a cutting tip portion connected pivotally within the passage of the head to the head and rotary with the head, the cam follower portions of the cutters

being engaged with the cam for cooperative movement therewith, and the cutting tip portions depending beneath the head for oscillatory cutting movement.

5. The combination which comprises a cutting tool including a rotary housing, cam means having angularly spaced radial lobe portions supported within the housing, and a pair of adjacently disposed cutters supported within the housing for opposed rotary oscillatory cutting action, the cutters having opposed beveled cutting faces positioned to form in cross section an inverted V-shaped configuration; a pantograph having a double stylus for co-operation with parallel grooves in a master template; and linking means connected to the rotary housing and to the pantograph stylus whereby the cutters are guided by the stylus to form in a workpiece an inverted V-shaped land according to the layout of said grooves.

6. An engraving tool which comprises a rotary housing, a cam shaft disposed coaxially for rotation within the housing, a cam attached rigidly to one end of the cam shaft and located within the housing, a head connected rigidly to the housing, the head having formed therethrough a passage, a pair of adjacently disposed cutters each having a cam follower portion and a cutter tip portion connected pivotally within the passage of the head to the head and rotative therewith, the cam follower portions of the cutters being engaged with the cam for cooperative movement therewith, and the cutting tip portions of the cutters depending beneath the head for oscillatory cutting movement.

30 7. An engraving tool which comprises a housing, rotary cam means having angularly spaced radial lobe portions supported within the housing, a head fixed to the housing, a pair of adjacently disposed cutters having cutting edges positioned to form an inverted V-shaped configuration in cross section, means for pivotally supporting the cutters within the head, and means for urging each of said cutters into separate and cooperative engagement with the cam means for oscillatory cutting action directed opposite to that of the other cutter whereby 40 the pair of cutters cooperate to form an inverted V-shaped land in a workpiece.

8. The combination which comprises a cutting tool having a rotary housing and a pair of cam-operated cutters disposed coaxially within the housing for opposed rotary oscillatory cutting action, a pantograph having a double stylus for cooperation with parallel grooves in a master template, and linking means engaged to the rotary housing and to the stylus for causing the cutters to follow movement of the stylus whereby the cutters cooperate to 50 form a land in a workpiece.
